UNITED STATES PATENT OFFICE.

JOHN Q. SHERMAN AND CLARENCE R. BUSCHMEYER, OF DAYTON, OHIO, ASSIGNEES
TO THE STANDARD REGISTER COMPANY, OF DAYTON, OHIO, A CORPORATION OF
OHIO.

AUTOGRAPHIC REGISTER.

1,385,588.

Specification of Letters Patent. Patented July 26, 1921.

Application filed May 25, 1917. Serial No. 170,805.

To all whom it may concern:

Be it known that we, JOHN Q. SHERMAN and CLARENCE R. BUSCHMEYER, citizens of the United States, and residents of the city 5 of Dayton, in the county of Montgomery and State of Ohio, have invented certain new and useful Improvements in Autographic Registers, of which the following is a full, clear, and exact description, reference being had to the accompanying drawings, forming part of this specification.

Our invention relates to electrically operated autographic registers, wherein an electric motor is provided which feeds the paper 15 in perfect alinement to a point for tearing off.

There has not been, to our knowledge, a successful motor operated autographic register in the past because the control of the feed has presented a difficult problem. It is necessary for the operator to touch a button to start the motor, and it should be provided that the device will come to a stop at the end of one complete feed of a section 25 of the paper strips, whether the operator carelessly leaves his finger on the starting button or not. Then again, except in the type of feed of paper known as the "Standard register" or "pin wheel" feed as first 30 developed in the patent to Schirmer, No. 940,481, it would be difficult to provide for proper feed by sections of the paper in a purely automatic manner with positive stops as are necessary between operations.

Thus it is our object to provide an electric 35 motor feed for autographic registers which is "fool-proof" and efficient and which may be readily attached to any "Standard register" or other type of machine wherein the feed of strips is accurately gaged by the operating devices.

These objects are accomplished by that certain construction and arrangement of parts to be hereinafter more specifically 45 pointed out and claimed.

In the drawings,

Figure 1 is a side elevation of the device.

Fig. 2 is a detail elevation of the switch and clutch portions partly broken away, and 50 showing the tripping pawl in operating position.

Fig. 3 is an end elevation of the device.

Fig. 4 is a side elevation of the latch arms.

Fig. 5 is a bottom plan view of the under one of the parts shown in Fig. 4. 55

The device is mounted on a plate 1 which may be screwed onto the register casing 2 by the screws 3 on the operating handle side. On this casing is suitably mounted the electric motor 4 having the rotor shaft 60 extension 5. This extension shaft is journaled at the outer end in a small journal 6 on the plate and is equipped at the end with a worm 7.

Keyed over the feed shaft 8 of the register, 65 which draws the slips of paper over the writing table portion of the register is the controlling cam 9, on the outer face of which is frictionally secured by means of facial contact therewith, the small toothed pinion 70 or worm wheel 10. It can be seen that when the motor operates the worm will drive the operating shaft and continue to do so as long as the current is on and the cam is free to move. 75

It is our purpose to provide a simple device for locking and unlocking the controlling cam, which device will stop the cam at exactly the same position at the end of each single revolution, thereby preventing the 80 slightest overthrow and providing a perfectly even feed of the paper in the desired sections. To this end there is provided the latch arms 11 and 12, with the latch arm 12 slidably mounted on the arm 11 by means 85 of screws 13 sliding in slots 14 in the arm 12. The arm 12 operates the switch and is pulled downwardly at the outer end by the spring 15 which pulls downwardly the arm 11. The arm 12 is moved rearwardly by the 90 spring 16 which is secured at its other end to the upper arm 11.

When in normal locked position, the arm 12 engages over the shoulder 16^a of the controlling cam, by means of its hooked nose 17. 95 The arm 11 has also a nose 18 which when the device is in normal position abuts the nose 17 on the outer edge thereof.

Mounted on the plate 1 behind the motor is a bracket 19, in which slides a reciprocating spring plunger 20 having a head 21 for operating it. Pivoted on this plunger is a 100

spring-pressed pawl 22 which stands normally on a line with the plunger. This pawl lies when in normal position with its end pressing down on the cut-away end portion 23 of the under arm 12. Upon depression of the plunger the end 23 of the arm 12 will be depressed. This arm is mounted, as stated, on the arm 11, and the arm 11 is pivoted at 24 in a small frame 25 on the plate 1. Thus the downward movement caused by the pawl will cause the two noses to be lifted off the shoulder on the cam and will leave it free to revolve.

The small pawl will be thrown out of the vertical by the nose 26 back of the cut-away end of the arm 12, as it moves rearwardly under spring tension, and as long as the plunger is kept in depressed position the pawl will remain tipped as it is thrown off center and will slide along the said cut-away end of the arm. The arm can rise up again at the inner end, due to its outer end falling over the nose of the cam, as will be described without affecting the plunger or the pawl, except to swing the pawl farther out of the vertical, and until the plunger is released it will be impossible to again depress the arm 12 at the inner end.

Leaving the switch for the present out of consideration, so as to describe the operation of the latch arms first, the controlling cam 9 being keyed to the feed shaft 8 of the register is operated counterclockwise as indicated by the arrows on Figs. 1 and 2, and during this rotation after the noses or hooks 17, 18, are raised by the depression of the plunger 20, they will be held by the spring 15 in contact with the periphery of the cam, and ride around this periphery in position to come in contact with the shoulder 16^a on the cam at the end of the revolution.

As illustrated in Fig. 1, the two latch arms 11 and 12 will be separated when the machine is at rest with the two hooks 17, 18, on the latches brought together. As soon as the latches are raised by the depression of the plunger 20, the spring 16 will bring the curved surfaces of the latch arms together and separate the hooks 17 and 18 as shown in Fig. 2.

It was stated that the arm 12 operates the switch. This member comprises a spring bar 27 which is fastened to one of the contacts at 28 and when released will move by its inherent springiness into contact with the other contact 29. Pivoted at 30^a to the plate 1 adjacent the frame which pivots the latch arms, is a bar 30 which is curved and has at its lower end a fiber or insulated pin 31 which swings the spring bar of the switch out of contact when the upper end of the said bar 30 is moved toward the controlling cam end of the device. The bar 30 is slotted at 32, and a pin 33 on the under arm 12 rides in the slot,

When the end 17 of the under arm is raised by the pawl as described, spring 16 will move it to the right or rearwardly and thereby move the pin in the slot 32 so as to release the bar 30 and permit the spring bar 70 of the switch to move to closing position.

As the switch is then closed the motor will operate, and as the cam is released or unlocked the motor will revolve the cam and cause the register to feed.

The feed will continue until the shoulder 16^a on the cam comes in contact with the hook 17, and by this contact the latch arm 12 will be shifted to bring the hook 17 in contact with the hook 18 of the other latch arm 11. At the same time the movement of the latch arm 12 will through the pin 33 swing the bar 30 so as to open the switch 27. This will cut off the power of the motor before the two hooks 17 and 18 are 85 brought together and the cam brought to a fixed stop. The motor, therefore, is not brought to a fixed stop at the same time that the current is cut off and in addition to this, inasmuch as the worm wheel 10 is loosely 90 mounted on the feed shaft 8 and drives the shaft through the cam disk 9 with which it has frictional engagement as heretofore described, there is no danger of burning out the motor, although the feed shaft itself for 95 the paper strips is brought to a full definite stop when the controlling cam has shifted the under latch arm into the position shown in Fig. 1 to bring the two hooks 17 and 18 together.

It is believed that the above description sufficiently describes the operation of the machine without further detailed description. It should be noted that various equivalent devices could readily be devised for 105 accomplishing the purposes of the above structure, and that the failure to mention those during the description of the device was not intended to effect a limitation of the claims that follow.

The various objects primarily stated are accomplished. The operating device is positively stopped at the end of each operation, and the continued depression of the tripping pawl will not result in the motor continuing to operate or the switch remaining closed, and a convenient and practical device is provided which gives motor operation to an autographic register.

Having thus described our invention, what we claim as new and desire to secure by Letters Patent, is:—

1. In a motor feed device for intermittent feeding devices, in combination with electric motor means for operating the feeding device, a switch therefor, and a controlling device comprising a rotary notched element, a pivoted arm having a nose to ride on said rotary element, and to latch into said notch, and a pawl to rock said arm, 130

said arm having a switch control member thereon.

2. In a motor feed device for autographic registers, in combination with motor means for operating the register, a switch, a rotary controlling element having a notch therein, a pivoted arm having a nose to latch in said notch, a second arm having a nose and slideable on the first mentioned arm so as to come in contact with said notch prior to the first mentioned arm, a pawl to lift both arms from the notch, and a switch control member associated with said second arm adapted to open the switch before positively latching the operating element.

3. In an autographic register a plate adapted to be demountably secured on the side of the register, a motor, a switch for controlling electric connections with the motor, and a motor driven member all mounted on said plate, a feed shaft for paper strips, and means for coupling the motor driven member to the said feed shaft comprising a pinion on the feed shaft, and a worm on the motor driven member, and said motor being mounted with its driven member in a plane substantially parallel to the plate, means for positively stopping the rotation of the feed shaft adapted to act directly thereon, and said pinion being frictionally held on the said feed shaft.

4. In a motor operating device for intermittent driving operations, a motor, a switch for controlling the motor circuit, a switch closing and opening member adapted to open the switch automatically and depressible means for setting the switch closing member into closing position, said depre-

sible means comprising in part an element which moves out of operative position after fulfilling one energizing operation whereby said switch may open although the depressible means is maintained in depressed position.

5. In a motor operating device for an intermittent feeding shaft, cam means on the feeding shaft, having a nose on its periphery, a motor connected to the said shaft, a switch for controlling the motor circuit, and a locking device and switch control for the mechanism comprising a pivoted arm having a hook to ride on the periphery of the cam, and a sliding arm on the pivoted arm having a like hook adapted also to ride on the cam, said sliding arm being normally maintained with its hook spaced away from the hook on the pivoted arm, the sliding arm being adapted to serve as a switch control.

6. A motor feed for feeding paper strips comprising a motor, an operating shaft for feeding paper, driving connection from the motor to the operating shaft of the register, and means for positively stopping and releasing the operating shaft at the close of complete operations comprising a pivoted latch member lying in a plane parallel to the side of the register, a second latch member slideable on the first latch member in a limited path, and means on the operating shaft for engaging said latches, so constructed that the initial engagement will be with the second latch, a switch for the motor, and means on the second latch for opening said switch.

JOHN Q. SHERMAN.

CLARENCE R. BUSCHMEYER.
